UNITED STATES PATENT OFFICE.

LAWRENC PACOREK, OF MILWAUKEE, WISCONSIN.

RECEPTACLE-COVER.

1,177,891.

Specification of Letters Patent.

Patented Apr. 4, 1916.

Application filed September 9, 1915. Serial No. 49,715.

To all whom it may concern:

Be it known that I, LAWRENC PACOREK, a subject of the Emperor of Austria-Hungary, residing at Milwaukee, in the county 5 of Milwaukee and State of Wisconsin, have invented certain new and useful Improvements in Receptacle-Covers, of which the following is a specification.

This invention relates to certain new and 10 useful improvements in receptacle covers.

The primary object of the present invention is to provide a cover for receptacles or wells that are particularly adapted to contain refuse, such as garbage, and in which 15 the cover is constructed to provide a receiving compartment that may be completely closed to prevent objectionable odors from escaping from the container when the refuse is emptied from the cover into the 20 container.

A further object of the invention is to provide a cover for a garbage receptacle or container in which there is provided a receiving compartment for the garbage that is 25 adapted to be closed at its upper end and subsequently opened at its lower end to cause the contents thereof to be emptied into the container while the lower sliding trap door is provided with a self-cleaning device 30 to render the device sanitary.

With these general objects in view and others that will appear as the nature of the invention is better understood, the same consists in the novel construction, combination 35 and arrangement of parts hereinafter more fully described, illustrated in the accompanying drawings, and then claimed.

In the drawings forming a part of this application and in which like designating 40 characters refer to corresponding parts throughout the several views:—Figure 1 is a perspective view of a receptacle cover built in accordance with the present invention. Fig. 2 is a longitudinal sectional view 45 of the same showing the sliding doors in closed position, the upper sliding door being shown in dotted line position and further illustrating the self-cleaning attachment for the lower sliding door, and Fig. 3 is a cross-sectional view taken on line III—III of Fig. 2.

Referring more in detail to the accompanying drawing, there is shown a box-like structure 5 that is of rectangular shape and 55 including side walls, end walls 6 and 7, and a cover wall 8. The receptacle cover 5 is

completely open at its bottom to facilitate the positioning of the same upon a suitable receptacle or container, while the cover wall 8 extends substantially half-way of the 60 upper end thereof and is provided with a central opening affording side extension legs 9 that are received on the upper edges of the side walls of the cover. A horizontal partition wall 10 is positioned within the 65 cover 5 beneath the cover wall 8 and is fixed thereto, a vertical transverse partition wall 11 being positioned at the ends of the cover wall 8 and the partition wall 9 and being disposed substantially mid-way the ends of 70 the cover.

As shown in Fig. 3, there is provided a pair of oppositely-arranged supporting ledges 12 upon which is slidably mounted a trap door 13, the side edges of which are 75 received in longitudinal grooves 14 provided in the inner faces of the side walls of the cover 5. The inner face of the end wall 6 is grooved as at 15 for the reception of the projected end of the trap door 13 to 80 constitute a receiving stop therefor. An eye-bolt 16 is carried by the opposite end of the trap door 13 and to which one end of an operating link 17 is connected, the said link being provided with a handle 18 on the 85 opposite end thereof that projects through an opening 19 provided in the end wall of the cover. By this construction there is provided a receiving compartment 20 for the cover, selectively closed at its lower end 90 by the trap door 13 while the upper end thereof is provided with a sliding closure door 21 that is slidably mounted in the opposite channel guides 22 and is limited in its closing movement by being passed under the 95 end member 23 of the channel guides and engaging the upper end of the end wall 6. An operating knob 24 is carried by the sliding door 21 and the door is limited in its opening sliding movement by engaging a 100 stop lug 25 fastened to the outer end of the upper wall 8.

In operation, the device may be suitably positioned upon a receptacle or container for garbage or other refuse and when it is 105 desired to empty refuse into the container, the sliding door 21 is moved through the channel guides 22 to permit the compartment 20 to receive the refuse. The door 21 may then be moved to closed position as 110 shown in Figs. 1 and 2 and the handle 18 of the link 17 grasped to slide the trap door

- 13 and permit the contents thereof to be emptied into the container positioned beneath the cover. In this movement a flexible scraper 26 secured as at 27 to the outer 5 face of the vertical partition wall 11 engages the upper face of the trap door 13 and effectively removes all refuse therefrom so as to render the device wholly sanitary and desirable for the purposes intended.
- 10 It will be noted that all disagreeable odors from the main container are prevented from escaping in view of the fact that the cover wall 21 is closed before the trap door 13 is opened.
- 15 While the form of the invention herein shown and described is what is believed to be the preferred embodiment of the invention, it is nevertheless to be understood that various forms, modifications and arrangements of the parts may be made without departing from the spirit and scope of the 20 invention as claimed.

What I claim as new is:—

A cover for garbage receptacles including a box-like structure, a pair of ledges secured 25 to the inner opposite side walls of the box extending from end to end thereof, a trap-door slidably mounted on said ledges, a central transverse vertical wall within the box, an immovable freely accessible flexible 30 scraper fixed thereto in engagement with said trap-door, a pair of channel guides secured to the upper face of said box, said guides being closed at one end and open at the other end, a cover wall slidably mounted 35 in said channel guides, and means carried by the receptacle for limiting the opening movement of the cover wall.

In testimony whereof I affix my signature.

LAWRENCE PACOREK.
